UNITED STATES PATENT OFFICE

143,954

DESIGN FOR A HAND MIRROR OR SIMILAR ARTICLE

Philip A. Derham, Rosemont, Pa., assignor to
Irving Zussman, Brookline, Mass.

Application May 26, 1945, Serial No. 119,743

Term of patent 7 years

(Cl. D86—10)

To all whom it may concern:

Be it known that I, Philip A. Derham, a citizen of the United States, residing at Rosemont, in the county of Montgomery, State of Pennsylvania, have invented a new, original, and ornamental Design for a Hand Mirror or Similar Article, of which the following is a specification, reference being had to the accompanying drawing, forming part thereof, in which

Fig. 1 is a front elevation of a hand mirror showing my new design;

Fig. 2 is a side view of the same;

Fig. 3 is a detail vertical sectional view on line 3—3 Fig. 1. The convex back of the hand mirror is substantially plain.

I claim:

The ornamental design for a hand mirror or similar article, substantially as shown and described.

PHILIP A. DERHAM.
